ELECTRIC SELECTING SWITCH

David Adam Christian, London, England, assignor to Siemens Brothers & Company Limited, London, England

Application June 14, 1933, Serial No. 675,665
In Great Britain July 1, 1932

7 Claims. (Cl. 179—18)

The invention relates to electrical selective systems such as automatic telephone systems, remote control systems and the like.

It is concerned with the selection of one of a number of circuits radiating from a centre. The control of the selection at such centre may be exercised from a point remote from the centre which point may be referred to as the control point.

Preferably the selecting switch is, until stopped to effect a connection, in continuous movement and a feature of this invention is that a selecting switch is driven by a mechanism readily adaptable to local sources of electric power. For instance, if an alternating current supply is available the mechanism may be a driving motor of the synchronous type used for the driving of electric clocks.

In one application of the present invention it is arranged that, at the centre, a selecting switch, to contacts of which the several selectable circuits are connected, also acts to connect a circuit through to the control point as required, in other words the selecting switch acts as a call finder in response to some action in any one of the circuits, the driving means for the switch consisting of an alternating current synchronous motor.

In the case of an electric switch which is in continuous motion and acts as a call finder as well as a selector, a definite starting point is required from which a selection may be made.

It is arranged, as a feature of the invention, that the different type of electrical control required in the case of selection, as opposed to call finder action, results from a variation of conditions under which current is supplied, at the control point, to a line leading to the centre.

According to a further feature of the invention, an electrical selective system has a selective switch provided with a synchronous driving motor and circuit arrangements whereby the switch is normally maintained in continuous operation in order successively to test the condition, calling or passive of a number of selectable circuits.

Arrangements according to the invention as applied to telephone subscriber lines connected to a centre from which a circuit (control-point line) continues to a telephone exchange will be described in connection with Figs. 1-4 of the accompanying drawings.

Of these drawings, Fig. 1 represents, diagrammatically the apparatus at the centre; Fig. 2 represents diagrammatically parts of the operating mechanism, Fig. 3 shows the cam timing;

and Fig. 4, comprising the two parts Fig. 4a and Fig. 4b, shows a circuit arrangement at the control point suitable for use with the selecting switch.

The selecting switch of Fig. 1 is a continuously moving selector CS arranged to close spring contacts 1 and 1, 2 and 2—to 12 and 12 by means of a cam, shown as CA1 and CA2, operating thereon. The selecting switch is driven by a simple type of self-starting alternating current synchronous motor MD, operated by current from 50 cycle alternating current mains, the circuit of the motor including certain normally closed relay and cam contacts, a1, b1, bd2. Other contacts, as r3 and c, are connected across contacts a1, b1, bd2, in order that, under certain conditions, the motor circuit may be closed in spite of the fact that one of the contacts a1, b1, or bd2 may be open.

There is, included in one wire B of the line (hereafter called the control-point line) that joins the control point to the centre at which the selector is situated, (hereafter called the centre), a relay A adapted when operated to open at contact a1 the motor circuit and thus to arrest the motion of the motor, the operation of the relay being brought about as the selecting switch, in closing in turn the springs appropriate to the selectable circuits (hereafter called subscriber lines) closes the springs of a subscriber line that is in a calling condition, that is, is looped, the current for the relay being fed from the control point.

Correct centering is insured by means of a cam CA3, which operates on springs c to ensure that though the motor circuit is broken at contact a1, the motor shall not stop until the circuit is also broken at springs c. Cam CA3 as well as that shown as CA1, CA2 may be taken to rotate in a clockwise direction.

The motor, on arrest, by means of the cam CA1, CA2, maintains the springs appropriate to subscriber lines closed, and thus maintains the subscriber line concerned in association with the control point over the control point line over which line the calling subscriber may, as by dialling, control the control point apparatus, relay A being rendered somewhat retarded in releasing by reason of rectifier AR connected in such manner as to present a high resistance to current flowing from positive connected to wire A to negative connected to wire B. It is thus conductive to current produced as a result of the dissipation of energy stored in the relay.

The selecting switch is arranged in one of its

positions, which for convenience may be referred to as the normal position and which is numbered 1 in Fig. 1, to connect a relay B across the two wires of the control point line, this relay having 5 in series with it a rectifier BR so connected that relay B will not operate with current flowing as above described, which may be regarded as the normal direction, and is the direction of flow (or rather the control point line polarity) when the 10 control point is in a receptive, as distinct from an initiative condition. Relay B, when the control point is in an initiative condition, a condition which is indicated by a reversal of the control-point line polarity and which obtains when the 15 control-point is calling a subscriber line, and when the selecting switch closes contacts 1, 1, operates, due to a reversed current, and at contact $b1$ opens the circuit of motor MD. The selecting switch moves under the control of spring c until properly centered and during the slight movement that takes place between the opening of contacts $b1$ and c, contacts $bc1$ and $bc2$ which are brought into operative relationship with a cam CA4 Fig. 2 by the operation of relay B, are operated, and 20 are cam held until the motor moves the selecting switch through position 12 in which position they are released. The loop across the control point line due to relay B indicates to the control point that the selecting switch is at its normal 25 position whereupon current is withdrawn, by the control point, from the line and relay B is released and the motor is restarted. By reason of the operation, or rather of the cam holding of contacts $bc1$ and $bc2$, relay B is maintained across the 30 control-point line in spite of the fact that the switch moves from normal and would but for the said contacts cut the relay from across the control-point line.

As soon as the exact period required by the 40 selecting switch to reach the contact springs appropriate to the wanted subscriber line has elapsed, a period which can be measured by a synchronous and synchronized motor at the control point moving from a normal to a marked position, reversed current is again connected to the control-point line and relay B, being still across the line, will again operate and open the circuit of the motor which after centering under the influence of springs c will stop.

50 Relay B since it has now operated with the selecting switch in an off-normal position brings contacts $bd1$ and $bd2$ into operative relationship with one of the projections a—j on cam CA5, Fig. 2, and these springs are operated and held until the motor moves the selecting switch through 55 position 12 in which position they are released. Springs $bd1$ cut relay B from across the control point line and substitute therefor relay R, in series with which is a rectifier RR which with the control-point line polarity reversed prevents relay 60 R from operating. Springs $bd2$ maintain the circuit of the motor MD open since, relay B releasing, it would otherwise be closed at contact $b1$.

65 Due to the position of the selecting switch, the control point line is extended to the subscriber line and the latter, in a manner to be described in connection with Fig. 4, is run, relay R being irresponsible to the ringing current.

70 At the end of the conversation the called subscriber hangs up and although relay R is across the line, by reason of rectifier RR being of high resistance to current in the reverse direction, signals the control point that the connection may be cleared. The control-point, in response to this signal, restores the control-point line polarity to 75 normal relay R as a result thereof operating and

at contact $r3$ closing the motor circuit. It also, at contacts $r1$ and $r2$ opens points in the control-point line whereby, as the selecting switch drives towards normal, calling extension lines passed on the way shall not interfere with the apparatus. In position 12, that is in the prenormal position of the selecting switch, through switch position the switch moves without stopping, the cam held springs $bc1$ and $bc2$, $bd1$ and $bd2$ are restored, the selecting switch being now again sensitive 10 to calling lines.

If some or all of the subscriber lines are to be provided with metering facilities, the meters being situated at the control point, the control point is so arranged as will be described in connection with Fig. 4, that, in order that the correct meter shall be connected to the metering circuit, when a calling subscriber line is extended to the control point a switch is rendered responsive to impulses representative of the identity of the calling subscriber line, the said switch after being set to an appropriate position in response to such impulses, causing the line current to be reversed whereby relay A is released and the selecting switch is restarted and driven to normal, 15 in which position due to the reversed current, relay B operates to stop the selecting switch and to cause the operation of cam springs $bc1$ and $bc2$.

The control-point now, in response to the loop 30 placed across the control-point line, withdraws all current from the line and so releases relay B the selecting switch thus being again driven. After the elapse of the exact period required for the selecting switch to have reached the calling line, a period measured by a synchronous and synchronized motor (ME Fig. 4) in travelling from normal to a position marked by the impulse-set switch (AS), normal battery is reconnected to the line and if the switch AS is in 40 fact set to the number of the calling subscriber line and as a consequence switch CS has reached the looped subscriber line, relay A operates and stops the motor.

The subscriber line is switched through to the 45 1st group selector and the call may then proceed in the usual normal manner. When the extension clears, relay A releases and the motor MD rotates to position 12 with all line potential removed as will be explained.

If the selecting switch had found no loop, due to the calling subscriber having hung up or to his having dialled a number other than his own, relay A would have failed to operate and the selecting switch would have driven to its pre-normal position.

The timing of the selecting switch may, perhaps, be more conveniently followed by reference to diagrammatic sketch Fig. 3, in which the moving parts CA1, CA2, CA3, CA4, and CA5 are represented as occupying the position referred to as normal or position 1, that is the position in which cam CA1, CA2 operates number 1 set of springs and connects relay B to the control-point line. Relay B, (as described in connection with Fig. 1) operates and opens the motor circuit (at contact $b1$ of Fig. 1). The circuit of the motor is, however, maintained closed by springs c until these springs are opened at cam recess 1. Relay B, in addition, moved trigger $tr4$ into the path of the projection on cam CA4 so that during the "overrun" of the motor, trigger $tr4$ closes springs $bc1$ and $bc2$. During this overrun, if the trigger is in the path of cam CA4, the supporting piece bsp is lifted onto ramp bcr (as will best be seen 65 70 75

in Fig. 2). The motor can now rotate in the manner described and the relay B will be maintained in connection with the control-point line until the gap in the ramp, passing position 12, 5 allows *bsp* to drop back to its normal position.

Similar cam action can be seen to take place with reference to contacts *bd* and cam CA5, except that these contacts cannot be operated in position 1 by reason of there being no projection on cam CA5 in that position. If, however, relay B is operated, when the switch has moved into any of the positions 2-11, with one of the cam projections *a-j* near to trigger *tr5*, 10 springs *bd1* and *bd2* will be operated during the 15 motor overrun.

In Fig. 2, relay B is shown as provided with an armature *ab* having an extension *ex* which carries triggers *tr4* and *tr5* and which abuts against contact spring *b1*. If relay B is energized, it attracts its armature *ab* thus moving trigger *tr4* into the path of cam projection CA4. The cam operates the trigger and lifts supporting piece *bsp* which, riding against the under slope *us* of ramp *bcr*, is forced to the right until, finally, 20 when it is lifted sufficiently high to become free of the under slope, it springs back to the left, but above, or rather upon the flat surface of ramp *bcr*.

Circuit arrangements, suitable for use at the 30 control point, under the supposition that the switch is to be used in connection with a telephone system are shown in Fig. 4. In this figure for convenience of finding contacts the circuit elements have been numbered E1-E12.

The control-point line is provided with apparatus which comprises (a) a number of relays (b) a uni-selector, represented by its wipers AS1-AS4 and by its driving magnet ASDM; and (c) a synchronous motor switch represented by 40 contacts *sm1* (E3), *sm2* (E1), *sm3* (E10) and *sm4* to *sm13* (E11) of which only *sm4*-*sm6* are shown, and by its motor ME. This motor switch may be, generally, similar to that at the "centre". Its contacts *sm1* to *sm3* are respectively in the 45 condition shown in Fig. 4 when the switch is passing through position 1, and upon leaving that position they are reversed. Its contacts *sm4*-*sm13* are closed successively as the switch passes through positions 2-11. This motor switch is normally at rest.

The control-point line can be, when in a receptive condition, extended by a line finder operating on terminals A1, B1, P1 and M1. It can be selected by a final selector FS (E1), operating on terminals A2, B2, and P2.

An incoming call, that is a call initiated at a subscriber station, will first be considered.

It will be seen that the line polarity is as indicated in Fig. 4, that is positive from earth, 60 through winding (II) of relay D, over contacts *ba14* and *co3* at rest, *j6*, *k1*, *k5*, *f6*, *co2*, wire A, and negative through windings (I) of relays D and Q, over contacts *k4*, *f5*, *co1* to wire B.

When motor MD, Fig. 1, in the course of one 65 of its revolutions, encounters a subscriber line which is in a calling condition, a circuit is completed for relays D and Q, and for relay A at the centre, rectifier AR presenting a high resistance.

70 Relay A stops motor MD as described.

Relay D has no effect that need be noted.

75 Relay Q at contact *q1* (E7) closes a circuit, over contact *ba2* for retarded release relay BB, and over contacts *aa2* and *n1* (which are off-normal springs of uni-selector AS) for winding

(I) of relay C. Although a circuit, similar to that for relay C, exists for winding (I) of relay BA, this relay does not operate since its operating time is greater than that of relay BB.

Relays BB and C operate.

Relay BB, at contact *bb1* (E2) earths wire P2 to guard the control point line; at contacts *bb4* and *bb5* (E7) isolates relay BA; at contact *bb6* prepares a holding circuit for relay C winding (II); and at contact *bb11* (E1) guards 10 relay D against later opening of contact *co3*.

Relay C, at contact *c1* (E7) further prepares its own holding circuit; and at contact *c4* (E1) connects dialling tone to the control point line.

The subscriber whose line has thus been extended to the control point, dials the number, on the "centre", of his own line, and in response to the dialled impulses, relays D and Q release and re-operate, relay D producing no effect.

Relay Q, at its back contact *q1* (E7) closes 20 and opens the circuit of magnet ASDM and of winding (II) of relay C. At its front contact *q1* it intermittently opens the circuit of relays BB and C but these are retarded release relays.

Uni-selector AS takes a number of steps depending upon the number of times relay Q releases. At its first step it opens its off-normal contacts *n1* (E1) whereby the circuit of winding (I) of relay C is opened. Relay C, however, holds 25 in the circuit of magnet ASDM.

Wiper AS3 provides an alternative earth for wire P2.

During dialling, relay A, Fig. 1, holds as its release is retarded by the short-circuiting effect of rectifier AR.

At the end of the train of impulses, relay C releases, due to its circuit being held open at the back contact *q1*.

Relay C, at contact *c2* (E2) closes a circuit from earth, over contacts *t10* and *c2* at rest 40 and *bb2* operated, through winding (I) of relay CO; and at contact *c4* (E1) removes dialling tone.

Relay CO operates, and at contacts *co1* and *co2* (E1), reverses the direction of current in the control-point line; at contact *co3* opens a point 45 in the original circuit of relay D (winding II) which point however, is bridged by contact *bb11*; and at contact *co4* (E5) closes a circuit for relay RA.

Relay RA operates and at contact *ra1* closes 50 a holding circuit, which is independent of contact *bb9*, for itself; at contact *ra6* (E1) closes a bridge across contacts *j6* and *k1*, to provide a circuit for relays D and Q independent of these contacts; and at contact *ra10* closes a bridge 55 across contact *co3*, also to maintain a circuit for relays D and Q.

Due to the reversal of the current in the control point line, relay A, Fig. 1, releases and at contact *a1* recloses the circuit of motor MD. 60 (Relays Q and D will also momentarily release). Motor MD will drive the switch at the centre to position 1.

As soon as switch CS moves from the calling line, relays D and Q will release (as the switch moves towards position 1 it may connect the control-point line to other subscriber-lines which are in a calling condition. Relays D and Q will operate in circuit with such lines but will have no effect. Relay A will not operate as such lines 70 are passed since the line polarity is reversed).

Relay Q, on releasing, opens the circuit of relay BB which releases.

Relay BB, released, at contact *bb2* (E2) opens the circuit from contact *t10* of winding (I) of 75

relay CO; at contact $bb3$ closes a circuit from earth, over contacts $na2$, $tt3$, etc., and $ba3$, winding (II) of relay CO, to hold this relay operated; and at contact $bb1$ (E4) closes a circuit from earth, over contacts $ra5$ and $bb1$ for winding (I) of relay J which operates.

Relay J, at contact $j1$ (E4) prepares a holding circuit for itself. This is a guard circuit and provides that if, due to the operation of relay 10 Q as switch CS passes other calling lines, relay BB should operate, relay J will still be held. Contact $j2$ (E5) provides a holding circuit from earth at contact $ra2$, for relay RA. If, in the above stated event, relay BB should operate and 15 open the holding circuit of relay RA, there will still be a holding circuit for relay RA, provided by contact $d5$, relay D also operating as the switch passes calling lines.

Contact $j4$ (E2) opens the holding circuit 20 through winding (II) of relay CO; contact $j5$ (E2) provides an alternative holding circuit through winding (I) of relay CO. If, in the stated event, relay BB should operate, relay CO will hold in a circuit from earth, over contacts $t10$, $c2$, $bb2$, and 25 its own winding (I). Contact $j7$ (E1) guards relays D and Q; and contact $j8$ (E7) opens the circuit of winding (II) of relay BA, this circuit being otherwise closed at contact $bb5$.

When switch CS reaches position 1, a circuit 30 will be closed from positive, through winding (II) of relay D, over contacts $j7$, $ra6$, $k5$, $f6$, $co2$, wire B of the control-point line, rectifier AR, contact $r2$, contact 1 of switch CS, contact $bd1$, rectifier BR, relay B, contact 1 of switch CS, contact $r1$, 35 wire A, contact $co1$, $f5$, $k4$, windings (I) of relays Q and D.

Relays Q and B will operate but the resistance of relay B is such that relay D will not operate.

Relay B, as described in connection with Fig. 1, 40 stops the motor and is connected across the line.

Relay Q, at contact $q1$ (E7) closes the circuit for relay BB which again operates.

Relay BB, at contact $bb2$ (E2) holds winding (I) of relay CO, at contact $bb1$ (E4) holds winding (I) of relay J to earth at contact $t6$; at contact $bb8$ (E5) opens the circuit of relay RA; at contact $bb10$ (E8) prepares a circuit for motor ME; and at contact $bb13$ (E7), prepares a holding circuit for itself.

50 Relay RA releases and at $ra6$ opens the circuit of relays D, Q and B; at contact $ra9$ (E8) closes a circuit for motor ME; and at contact $ra11$ (E7) closes a holding circuit for relay BB.

Relays Q and B release, (relay D was not operated).

Relay Q at contact $q1$ opens the circuit of relay BB but an alternative circuit will shortly be closed.

Relay B recloses the circuit of motor MD as described.

Motors MD and ME now rotate in synchronism, the former maintaining cam contacts $bc1$ and $bc2$ closed, and the latter closing various contacts sm . Of these contacts those which will be referred to as $sm1$, $sm2$ and $sm3$ remain closed until the motor reaches position 12, and those which will be referred to as $sm4$, $sm5$, $sm6$, etc., operate in turn as the switch occupies positions 2, 3, 4 etc. Contact $sm1$ (E3) changes over and opens the original start circuit of motor ME; it closes an alternative circuit from earth over contacts $bb15$, $k9$, $t1$ and $sm1$. Contact $sm2$ (E1) closes a circuit from earth, over contacts $sm2$, $ra11$, $k8$, $bb13$, and $ba2$ for relay BB. Contacts 70 $sm4$ (E11), $sm5$, $sm6$, etc., in turn, connect earth

to the contacts in bank AS2 of switch AS which, it will be recalled, has been set by the calling subscriber to a position corresponding to his line number.

When motor ME reaches a position which corresponds to the calling line, that is to the setting of switch AS, a circuit is closed from earth over contact $fi3$ (E11) at rest, the appropriate contact $sm4$, $sm5$, $sm6$, etc., wiper AS2 in its set position, contacts $ba6$, $q4$, $co9$, $t3$ and winding of relay T.

Relay T operates and at contact $t1$ (E8) opens the circuit of motor ME whereby the motor is brought to rest in a position depending on the number of the calling line; at contact $t2$ (E10) 15 closes a circuit from earth, over contacts $ba1$, and $t2$ for relay TT; at contact $t3$ (E11) closes a holding circuit for itself from earth at contact $ji0$; at contact $t5$ (E5) opens a point in the circuit of relay RA against subsequent operation of contact $d5$; at contact $t6$ (E4) opens the circuit of relay J which, however, does not immediately release; at contact $t7$ (E7) opens to prevent closure (at contact $tt4$) of a circuit for winding (II) of relay J, at contact $ti0$ (E2) opens the circuit of relay CO which releases; at contact $ti2$ (E1) 20 place a short circuit across relay Q to provide a balanced bridge circuit; and at contact $ti3$ completes the loop which, as motor MD has driven in synchronism with motor ME, is completed at 25 the centre to the calling subscriber-line.

Relay TT has no present effect. It closes, however, at contact $tt2$ (E10), a holding circuit for itself.

Relay CO, at contacts $co1$ and $co2$, re-establishes the original direction of connection in the control-point line; at contact $co3$ re-establishes the original circuit for relay D; and at contact $co11$ (E11) restores relay T to dependence on contacts $k6$, $sm4$, etc. 30

Relays D and A, the latter due to the direction of current in the control-point line being restored, operate.

Relay A opens the circuit of the motor MD and brings switch CS to rest in association with the 45 calling line.

Relay D, at contact $d1$ (E9), closes a circuit for winding (II) of relay Q and at contact $d4$ (E4) provides a holding circuit for relay J.

Relay Q, at contact $q2$ (E12) closes a circuit for 50 relay ST which is the starting relay for line finders, not shown, one of which hunts for the calling line, the line being marked at wire P1 in a circuit which includes contact $ti1$ (E3) and relay K. Relay Q at contact $q1$ re-operates relay BB but 55 without effect, at contact $q3$ (E10) closes an alternative circuit for the holding of relay TT.

When a line finder shall have found the calling control-point line, relay K will operate.

Relay K, at contact $k1$ (E12) opens the circuit 60 of relay ST; at contact $k2$ (E3) closes a holding circuit for itself; at contact $k3$ (E6) connects up the meter M of the calling subscriber, the correct one having been selected by wiper AS4; at contacts $k4$ and $k5$ connects the control-point line wires B and A respectively to line finder wires B1 and A1 respectively and, at the same time disconnects relay D; at contact $k6$ (E11) opens the circuit of relay T which releases; at contact $k7$ 65 (E10) opens one of the holding circuits of relay TT; at contact $k8$ (E7) opens the holding circuit of relay BB (which, however, holds at contact $q1$ but without effect) and closes a circuit which includes contact $sm2$, for relay KR; and at 70 75

contact k_9 opens a point in the circuit of motor ME against the release of contacts bb_{15} and t_1 .

Relay KR, at contact kr_3 (E7) opens a point in the homing circuit of switch AS, against the release of contact bb_{12} .

The meter having been connected up, metering can be effected in any suitable manner.

Relays D and then Q (contact d_1) (E9) release, contact q_1 opening the holding circuit for relay BB.

Relay T releases and, at contact t_2 (E10) opens the alternative holding circuit of relay TT; and at contact t_6 (E4) removes the holding circuit of relay J from dependence upon relay D.

Relay BB releases and at contact bb_7 opens the circuit of relay J, which releases.

Everything is now dependent upon relay K, that is, ultimately upon the calling subscriber maintaining a loop on wires A1, B1. When, eventually,

the caller does hang up, in a manner well known earth is removed from wire P1 with the result that relay K will release and will, at contact k_3 (E6), open the metering circuit; at contacts k_4 and k_5 (E1) restore the control-point line connection towards relay D; at contact k_8 (E7) open the operating circuit of relay KR which, however, holds over contacts sm_2 , ra_1 and kr_4 ; and at contact k_9 close a circuit from 50 cycle alternating current source for motor ME.

Relay A releases due to the subscriber hanging up, and re-closes the circuit of motor MD whereby the motor is again set into motion, and so continues until arrested as above described or as below to be described.

Motor ME rotates until it occupies its normal position with all contacts sm in their normal conditions. Contact sm_2 opens the circuit of relay KR which releases.

Relay KR, at contact kr_1 (E1) reconnects relays D and Q to the control-point line, and contact kr_3 completes the circuit for magnet ASDM.

Magnet ASDM drives switch AS to its normal position in which position the self drive circuit is opened at wiper AS1.

A connection to a line on the centre, Fig. 1, and the association of the control-point line with an extension as a called extension is brought about as follows:

Connection is made, by a suitable final selector, to the control point apparatus, at the terminals

P2, A2, B2, and assuming the line to be free a circuit will during the fleeting test period be completed over wire P2 (E2), wiper AS3 in normal position, contacts ba_1 , bb_1 , bb_2 and winding (I)

of relay CO.

Relay CO operates and at contacts co_1 and co_2 (E1) reverses the connections to wires A and B, this being, at present, a preparatory operation; at contact co_3 disconnects the line until the circuit is

ready; at contact co_4 (E7) closes a circuit through winding (II) of relay BA, this relay being, however, retarded in operation in order, at contact ba_{12} (E1), to guard relay AA against ringing current;

at contact co_6 (E2), prepares a holding-circuit for itself, eventually to be closed at contact ba_9 , over contacts tt_3 , etc., and ba_9 (first unoperated and then operated when q_5 is included) to its winding (II).

Ringing will be tripped and the connection switched through, at the final selector, in the usual manner and eventually relay BA will operate.

Relay BA, at contact ba_2 (E1) opens any possible circuit for relay BB; at contact ba_9 (E2) brings contact q_5 into the holding circuit of re-

lay CO as described; at contact ba_1 (E2) returns busying earth to wire P2; at contact ba_{12} (E1) removes the short circuit from relay AA; and at contacts ba_3 and ba_4 (E1) polarizes the control-point line as follows: earth, contacts f_1 , ba_3 , ba_4 , co_3 , j_6 , kr_1 , k_5 , f_6 , at rest and co_2 operated, wire B. Negative is connected to wire A as may be seen.

Relay AA operates in a circuit completed at the final selector, and at contact aa_1 (E7) opens the original circuit of relay BA and at the same time closes an alternative holding circuit through winding (I), and an operating circuit for relay C.

Relay C operates, and at contact c_1 prepares a holding circuit for itself in series with magnet ASDM of switch AS.

Meantime motor MD has been continuing to drive switch CS towards position 1. If, in approaching position 1, it passes extension lines that are in a calling condition, it will not regard them as, due to the operation of relay CO, either there is no current until relay BA operates, or when relay BA operates, the direction of current is wrong for the operation of relay A. After the operation of relay BA, relays D and Q would operate but contacts f_1 maintain a loop for relay AA.

When switch CS reaches position 1 a circuit will be closed for relay B, which as before brings switch CS to rest and closes cam held contacts bc_1 and bc_2 . The circuit includes relays D and Q the latter of which operates. Relay D, however, cannot operate in series with relay B. Relay Q at contact q_5 (E2) opens the circuit of relay CO. This relay will either hold in an alternative circuit which includes contact c_5 , or if relay Q operates before relay C, will re-operate in that alternative circuit.

The system is now ready to respond to a further train of impulses from the calling line which is approaching the extension over the final selector. These impulses are repeated to relay AA which responds thereto and, at contact aa_1 (E7) causes switch magnet ASDM to step wipers AS to a position which depends upon the number, on the party line centre, of the wanted extension. The circuit is, contacts aa_1 , ba_3 , c_1 , relay C, magnet ASDM. With the switch off-normal, the circuit of winding (I) of relay C is opened at contacts n_1 .

When dialling shall be completed, relay AA will be held operated and, consequently, relay C will release and relay BA will be held over winding (I).

Relay C, released, will at contact c_1 open its own holding circuit through winding (II); at contact c_3 (E8) prepare a circuit for motor ME, to 50 cycle alternating current; and at contact c_5 open the circuit of relay CO.

Relay CO will release and at contact co_3 open the line circuit, whereby relays Q and B will release, the latter to connect motor MD to a source of 50 cycle alternating current. At contact co_4 (E7) relay CO will open the circuit of winding (II) of relay BA which will not, however, release as it has a circuit over winding (I); at contact co_8 (E8) it will close a circuit for motor ME; and at contact co_9 (E11) it will prepare a circuit for relay T.

Motors ME and MD rotate synchronously, and as the former does so, as before it successively closes contacts sm_4 , sm_5 , sm_6 etc. When eventually that contact sm which corresponds with the position into which switch AS has been set, is closed, relay T operates and at contact t_1 (E8) 75

- opens the circuit of motor ME which is thus brought to rest. It also, at contact t_9 (E2) closes a circuit for relay CO and at t_{13} prepares the circuit of relay D; other contacts of relay T need not here be noted.
- Relay CO, at contacts co_1 and co_2 reverses the line connections, whereby relay B, Fig. 1 is operated, to arrest the motion of motor MD; at contact co_3 , completes the circuit for relay D; at contact co_{10} (E10) prepares a circuit for relay TT; and at contact co_{11} (E11) opens the circuit of relay T.
- Relay D operates and at contact d_1 (E9) closes a circuit for winding (II) of relay Q.
- Relay T releases and, at contact t_2 (E10) closes a circuit which includes contacts co_{10} and sm_3 , for relay TT; and at contacts t_8 and t_9 (E2) opens the circuit for relay CO.
- Relay TT (E10) operates and at contact tt_1 closes a holding circuit for itself; at contact tt_3 (E2) opens the circuit of winding (II) of relay CO; at contacts tt_5 and tt_6 (E1) connects ringing current to line A.B; and at contact tt_{18} (E2) connects ringing tone to the calling subscriber.
- Relay CO on releasing, at contacts co_1 and co_2 restores the line connections but at contact co_3 opens a point in the circuit of relay D; at contact co_4 opens a point in the circuit of winding (II) of relay BA; at contact co_9 (E11) closes a circuit for relay T which includes a contact sm_4-sm etc., and at contact co_{13} (E1) prepares a self-drive circuit for magnet ASDM.
- Relay T re-operates and at contact t_2 closes an alternative holding circuit for relay TT to earth at contact tt_2 .
- When, in response to the ringing current, the called extension replies, relay F will operate and at contact f_1 (E1) remove direct earth from the line; at contact f_2 (E1) remove ringing tone from wire B2; at contacts f_3 and f_4 remove ringing current from line A.B.; at contacts f_5 and f_6 reverse the connection of the line to prepare for the operation of relay R; at contact f_7 (E1) closes a circuit around contact co_3 to provide a circuit for relays D and R; at contact f_8 (E8) open the start circuit of motor ME against its restoration; at contact f_9 (E1) place a short circuit across winding (I) of relay Q to present a balanced bridge; at contact f_{10} (E9) close a circuit for winding (II) of relay Q; at contact f_{11} (E1) removes a short-circuit from across its own winding (II) to provide for its own holding, at contact f_{12} renders relay AA dependent on contacts d_2 and q_7 ; and at contact f_{13} opens the circuit of relay T.
- Relay Q at contact q_7 (E1) provides for the holding of relay AA dependent on contact d_2 , relay D operating sooner than relay Q which has its winding (I) short circuited.
- When either party to the connection hangs up the apparatus is restored. Thus, if the calling subscriber hangs up contact z (E1) is opened and if the called subscriber hangs up, contact d_2 is opened and in either case relay AA is released. When the called party hangs up relay A, Fig. 1, also releases.
- Relay AA, at contact aa_1 opens the circuit of relay BA which releases.
- Relay BA at contact ba_5 (E7) closes a circuit for driving magnet ASDM whereby switch AS is self-driven to normal; and at contact ba_7 opens the circuit of relay F.
- Relay F, at contact f_{10} (E9) opens the circuit

of relay Q which, if relay D has also released, releases and at contacts f_5 and f_6 restores the direction of the line connections.

Relay Q, upon release, at contact q_3 (E10) opens the circuit of relay TT.

Relay TT, at contact tt_8 (E8) closes a circuit for motor ME which restores, and at contact sm_1 , opens its own homing circuit.

The restoration of the direction of current to the line provides a circuit for relay R, Fig. 1, which at contact r_3 closes a circuit for motor MD, the circuit for relay R including contacts bc_1 , bd_1 and bc_2 .

When switch CS arrives in position 1, contacts bc_1 and bc_2 and bd_1 are opened whereby relay R releases and opens the circuit of motor MD.

The apparatus is now restored to its normal condition.

I claim:—

1. In a selecting system, a selecting switch having contacts, an alternating current synchronous driving motor for operating the switch, a plurality of circuits connected to said contacts, means for operating said switch to select one of said circuits, and said switch operated in response to control over one of said circuits.

2. In a selecting system, a selecting switch having contacts, an alternating current synchronous driving motor for operating said switch, and circuit arrangements for operating said motor to continuously operate said switch to successively test the calling or idle condition of said contacts.

3. In a selecting system, a selecting switch, lines accessible thereto, means for operating said switch to connect with said lines, a common line leading to the switch, a pair of devices for controlling the switch, means for reversing current in the common line, one device operated to stop the switch if a calling one of said lines is connected with when the current is in one direction over the line, and the other device operated by current of another polarity independent of the connected with line.

4. In a selecting system, a line, a selecting switch therefor, a synchronous motor operating the switch, a plurality of polarized devices for controlling the motor, and means for connecting opposite polarities of current across the line to cause said devices to operate selectively to start, stop and restart the motor by connecting and disconnecting alternating current thereto.

5. In a selecting system, a selecting switch, a line leading thereto, a plurality of relays in the switch each having a rectifier connected thereto in a different manner, means for connecting said relays to the line at different stages in the operation of the switch, and means for reversing the current in the line to control the devices to start, stop and restart the switch.

6. A selecting system as claimed in claim 5 in which the reversal of current in the line is controlled from the switch.

7. In a selecting system, a selecting switch, a common line leading thereto, lines accessible thereto, a synchronous alternating current motor for operating the switch to seize a line, controlled over the common line, and another synchronous alternating current motor at the other end of the common line operating in synchronism with the switch motor to control its operation.
